UNITED STATES PATENT OFFICE.

NELSON B. JOHNSON, OF WINTHROP, MASSACHUSETTS.

FLUID-PRESSURE PUMP.

Application filed August 19, 1921. Serial No. 493,647.

To all whom it may concern:

Be it known that I, NELSON B. JOHNSON, a citizen of the United States, residing at Winthrop, in the county of Suffolk and 5 State of Massachusetts, have invented a new and useful Fluid-Pressure Pump, of which the following is a specification.

This invention relates to a pressure pump adapted to be used for creating pressure 10 on liquids and forcing them to higher levels. The principal objects of the invention are to eliminate the necessity of mounting the air tight receiver for the liquid in such a way as to rock or otherwise move in performing that operation; to provide an 15 exceedingly simple and durable positive acting motor operated by fluid under pressure for controlling it and having connections for performing the necessary operations of 20 opening and closing the supply valves all capable of being located outside of the receiver to facilitate repair, and to provide an improved displacement float, for controlling the operation of the motor, which has 25 no buoyancy in water.

In connection with the first of these objects, this invention comprises the use of a stationary air tight receiver for the water to be pumped, thus eliminating the cumbersome 30 some rocking movement as well as the trunnions or glands which otherwise are necessarily a part of the same and thus materially simplifying the old device and permitting it to work indefinitely without danger of its 35 being stopped on account of trouble with packings or trunnions. Further objects, advantages, and features of the invention will be described below.

Reference is to be had to the accompanying drawing in which—

Fig. 1 is a central longitudinal sectional view of a preferred embodiment of this invention showing some of the parts in side elevation;

Fig. 2 is a similar view in a different condition, showing a better form of float;

Fig. 3 is a section of the motor operating device on the line 3—3 of Fig. 1;

Fig. 4 is an enlarged central sectional view of the valve construction, and

Figs. 5 and 6 are sectional views on the lines 5—5 and 6—6 respectively of Fig. 4.

Although this invention is capable of general use, it is also adapted for returning the 55 water of condensation back to the boiler or other source from heating systems, drying

systems and various other devices, condensing steam for different purposes. It has been the practice heretofore to provide pressure pumps of various makes for similar 60 purposes. These devices of large type that will handle large quantity of water usually depend for their operation in a tilting movement of the water receiver for opening and closing the inlet and the outlet valves. The 65 receiver when empty stays in one position and when filled up to a predetermined level the added weight rocks it over. In order to provide for this tilting movement the receiver has to be mounted on a pair of trunnions or glands through one of which the 70 water is discharged. The other admits steam or compressed air for exerting pressure on the surface of the water to force it out. These glands require packing to prevent 75 leaking, or in some cases they are constructed with a ball and socket joint. In the latter case they have to be kept oiled to prevent sticking and in the former case the packing gives much trouble as it is difficult 80 to pack the trunnions or glands so accurately that there will be no leakage and still leave them loose enough not to retard the tilting action. At the best, all trunnions 85 are troublesome and after some use will be found to be either leaky or in a condition to stick and therefore prevent the entire operation of the system. Furthermore, these receivers are made of rather large size in some 90 plants and have to be built of heavy steel plates in order to stand the high pressure. They are arranged to operate after collecting from 20 to 40 gallons of water and the combined weight of the receiver and water 95 on the trunnions is so great that this type of pump is subject to common complaint on account of the sticking of the pivots and the failure of functioning.

The operation of such a pressure pump requires closing of the valve through which 100 the exhaust steam is admitted and the opening of another valve to admit fluid under pressure when enough water is collected in the receiver and it is time to cause the pump to operate to discharge it. This, as stated, has been accomplished by connections operated by the tilting of the receiver itself. Then, after the water has been forced out by the fluid pressure, that valve has to be closed and the 105 water valve opened also, by the reverse tilting of the receiver. So far as I am aware, 110

the above indicated type is the only one that has proved capable of handling a large amount of water and working under high pressure. The small float action devices 5 are useful only for low pressures and small quantities of water. This invention is designed in such a manner that comparatively large quantities of water can be discharged and high steam or air pressures used and at the same time avoid the disadvantages of the tilting receiver.

Referring to Fig. 1, I have shown a strong stationary steel receiver 10 mounted on heavy fixed supports 11 and capable of sustaining high pressure and carrying a large body of water. In the form shown, I have indicated it as provided with an inlet 12 which is supplied with water from a pipe 13. The inlet 12 is carried above the water level. The object of this is to prevent steam, that finds its way to the pump, agitating the water. I have found in practice, that, if the inlet enters just through the bottom of the pump, steam would agitate 20 the water, affecting the displacement weight, which in turn acted on the motor control valve, and allowed steam to act on the piston, making the pump action erratic and irregular. This trouble I have overcome by 25 carrying the pump inlet above normal water level so that these difficulties cannot occur. The pipe 13 is connected with the exhaust from the heating system, or with a feed water heater, or the like, to supply water to 30 the receptacle 10. The admission of the water is controlled by a check valve 14.

At the bottom of the receiver is a water pipe 7 which is provided with an outlet 8. This is provided with a check valve 9 to 40 permit water to be discharged as desired. The outlet will naturally be connected with any desired device to which water is to be supplied.

A pipe 15 leading into the receiver 10 is supplied with high pressure steam, compressed air, or other fluid through a passage 17 in a casing 18. This is controlled by a steam admission valve 20 connected with a live steam pipe connection 54. This valve 45 has a stem 21 operated by a lever 22 pivoted on a link support 23. The passage 17 is also connected with a relief valve 19 similarly operated by a lever 26. These two levers are provided with weights 24 and 50 25 for holding the valves closed when they are free to act. The relief valve 19 is held open by a weighted operating lever 27 which has links 28 and 29 for operating the levers 22 and 26. The lever 27 also has 55 a link 30 for operating a weighted lever 30^a which controls a water spray valve 31 for a purpose to be described.

A steam baffle plate 16 is shown where the steam enters the top of the pump receiver, for the purpose of displacing the

water. The special object of this baffle is to direct the flow of steam so that the surface of the water is not agitated. It also prevents water hammer that is so often caused in pumps of this makeup by allowing high pressure steam to be entrapped in the water contents. The said baffle also allows for the expansion of steam as soon as it leaves the pipe connection, by having many times the area of the steam supply pipe, and by having its two ends open. A steam blanket is noiselessly formed above the surface of the water and pressure is quickly and noiselessly generated, equal to that carried in the boiler, when required, causing the water contents of the receiver to quickly discharge into the boiler.

Located in the receiver 10 is a float ball 32, preferably formed of cast-aluminum and hollow. This float ball is made so as to stand high external pressure, more than is ever used in steam boilers employed for manufacturing purposes. It is also made so as to overcome the difficulty encountered by the leakage of the water through the aluminum under very high pressure. For this purpose I simply make the float of such shape that it has at the bottom a straight line communicating with the inlet and outlet in a straight line. This is connected with a pipe 35 on a line tangent to or in line with the bottom of the float. Thus when the float rises to the dotted line position in Fig. 1 all the water will drain out. This happens once during each cycle 100 of operations. Therefore there is never any chance of water logging and no complicated internal piping.

The float is rigidly connected with a lever 35 pivoted on a horizontal central shaft 36 and having on the other arm a counter weight 37. It is counterweighted to reduce its weight in water substantially to nothing. The shaft 36 and lever 37 are provided with a tube 38, preferably of copper, and terminating in a pet cock 39 on the outside of the receiver to constitute a vent if ever the float should become filled with water.

Should the float 32 become completely filled with water, of course it would cause the float to remain resting on the bottom of the receiver 10 as shown in Fig. 1. Now to remove the water from the float 32 it is only necessary to raise the lever 27 and hold it up, opening the steam admission valve 20. This allows steam to flow into the pump receiver 10, discharging its water contents. After water has been discharged from the pump receiver 10, the petcock 39 should be opened and the pressure in the pump receiver will, in a very few seconds, expel all water from the float 32 through the tube 38 and the petcock 39. After this has been done, the float is again buoyant and ready to function and the petcock 130

should be closed. Thus a positive means of keeping the float 32 in functioning condition is provided without ever having to take the pump apart and make repairs due to 5 water logged float.

Another form of float is shown in Fig. 2. This float 32^a consists of a hollow ball of sheet copper. A tube 33 is inserted extending from the bottom to the top of the float 10 and opening beyond the top where it is provided with a bend or goose neck. Both ends are open. This equalizes the pressure inside the float with the external pressure of steam or air in the receiver and causes any 15 water in the float ball to be discharged within the tube 33. When pressure is exhausted from the receiver in the operation of discharging the water therefrom, any water which may have leaked into the copper 20 float will be forced to rise in the tube 33 by the expansion of the air trap in the float above its level. This expansion is permitted at this time by the reduction in the pressure outside the float. Therefore when there is 25 any water in the bottom of the air float, the pressure above it will be equal to the pressure of the air or receiver and when that pressure is reduced the excess water will be discharged through the tube. Thus there 30 is never any chance of water-logging and no internal complicated piping.

On this shaft 36 in either form is fixed a frame or lever 40 comprising two rigid arms shown as arranged at about 90° from 35 each other. Each is provided with an adjustable bracket 41 having a roll 42 thereon. These rolls extend inwardly from the arms or toward each other.

Pivottally mounted on a shaft or stud 43 40 is a weighted lever 44 having a roll 45 on its lower short arm. This roll works between the two ends of a yoke 46 and is adapted to move it back and forth a short 45 distance as will be seen by comparison of the extreme positions shown in Figs. 1 and 4. The yoke 46 is fixed to a valve stem 47 provided with a control or pilot valve 48. This valve controls the admission of steam through a port having a valve seat 49 and 50 is closed when no water is being discharged. This port, and therefore the valve casing, is supplied with live steam through a pipe 54 from a source of supply. The valve casing 50 has a relief port 51 controlled by the 55 other end of the valve 48. The weighted lever 44 tends to hold the valve 48 yieldingly either in closed or open position as placed by the float. The stud 43 is mounted on the plate 30^b.

The casing 50 has an outlet 52 that communicates through a pipe 53 freely with the top of a piston pressure chamber 55. This chamber consists of a pipe casing closed at the top and bottom by caps and 60 containing water nearly up to its top. It

is shown as carried by one of the supports 11. It has in it a copper tube 56 which extends through its wall and into the motor cylinder 58. The piston pressure chamber 55 forms a pocket on which the steam pressure 70 is allowed to act to force water into this cylinder. In the motor cylinder is a piston 59. The piston 59 is arranged with suitable packing 60 on its top side and a seat 61 is formed in the upper end of the 75 piston cylinder so that when the piston is in its uppermost position the packing on the piston is held tightly against said seat, thereby making the piston water tight, while the pump is discharging. This is very 80 advantageous when these pumps are used for boiler water feeders, as the piston has to remain in its upper position for long periods, and with the packing on the sides of the piston only, leakage is very apt to occur, and renewing of packing would be required much oftener. I use the side packing 85 also. It is to be noted that this arrangement allows the motor piston to be operated by water instead of steam. This slows down 90 the action very much so that high pressure can be used without acting too suddenly. The piston has a rod 62 which pivotally supports the lever 27 and operates it

The operation of the device is as follows:—Let it be assumed that the water is substantially exhausted from the receiver so that the float 32 has reached substantially its lowest position as shown in Fig. 1. This results in turning the frame 40 over to the 100 right from the position shown in Fig. 4 to that shown in Fig. 1. This throws over the lever 44 and closes the valve 48, opening the relief port at 51. This cuts off the 105 live steam from the port 52 and pipe 53. The first result of this is to remove the pressure from the top of the water in the piston pressure chamber 55 and allow the level of the water therein to rise. In other words, the counterweight 65 on the lever 27 can 110 now force the piston rod 62 down and the piston 59 with it, the water under the piston 50 flowing through the tube 56 back into the piston pressure chamber. The lever 27 thus moves to the position shown 115 in Fig. 1. This closes the valve 21 so as to shut off the live steam pressure from the valve 48, opens the relief valve 19 to permit the steam to be exhausted, and also opens the water spray valve 31 and admits 120 the water through the water spray pipe below to condense steam in the receiver and thus create a partial vacuum therein. The result of all this is to facilitate the flow 125 of water in through the inlet 12 to replace that which has been taken out.

As the water rises in the receiver the float 32 rises with it and finally it reaches the point shown in Fig. 2 at which time it turns the frame 40 over to the left and takes 130

the lever 44 with it to the position shown in Figs. 2 and 4, thus opening the valve 48 and closing the relief 51. This admits live steam through the port 52 and pipe 53 into the motor casing 55 which exerts pressure on the top of the water in the piston pressure chamber below. The effect of this is to drive water up the tube 56 into the motor cylinder 58 and lift the piston 59 so as to raise the lever 27 with its counter-weight. The effect of this is to open the steam valve 21, allowing the live steam to flow into the receiver through the inlet 15 against the baffle plate 16 and again exert steam pressure on the top of the water therein. The relief valve 19 is also closed and the water spray valve 31 by the lever 27 as indicated in Fig. 2.

It will be seen therefore, that I have provided a stationary receiver which can be made as large and heavy as may be desired without interfering with the operation of its connections, which will be capable of performing all duties that can be performed by any piston pump and which can handle water heated to high temperatures without trouble, and it also avoids the trouble ordinarily encountered when feeding water into boilers under high pressure by means of piston pumps due to leakage past the packing glands or piston. The wear is obviously reduced, in fact almost entirely eliminated, and the necessity for attention and repairs also. The discharge of the water through the outlet 8 is capable of taking place at all times whether the steam valve is open or closed. The pump is especially valuable for supplying feed water to high pressure boilers for these reasons. Inasmuch as an absolute predetermined amount of water has to be discharged by the pump for each cycle of operation, this type of control keeps the steam pressure on the piston water pressure chamber until the predetermined level of the displacement weight has been reached in the pump receiver. The valve, at this point, is suddenly closed against steam pressure and the relief port opened from the motor piston. With such action slight leakages do not affect the action of the pump.

Steam pressure cannot be communicated from the pump receiver to the control valve that would affect the same. The valve cannot be prevented from operating by packing a valve stem too tight. The quick action of the valve stem also prevents wire drawn seats. The small area of the high pressure steam port allows of very easy closing against the very highest steam pressure, and the friction of the packing around the valve stem keeps the valve closed. This packing gland is made exceptionally deep, so as to hold plenty of packing for this purpose.

Although I have illustrated and described only one form of the invention, I am aware of the fact that modifications can be made therein by any person skilled in the art without departing from the scope of the invention as expressed in the claims. Therefore, I do not wish to be limited to all the details of construction herein shown and described but what I do claim is:—

1. In a fluid pressure pump, the combination with a receiver for the water to be pumped, having an inlet for admitting fluid under pressure on the surface of the water therein, and a vent, of an inlet valve, a vent valve for alternately venting and closing the receiver, means for operating both valves, means connected with the valve operating means for holding the vent valve open when water is flowing into the receiver, and for closing the vent valve when water is to be forced out of the receiver, means whereby the valve operating means will act to positively close the vent valve before opening the pressure inlet valve, and means operated by the fluid under pressure in the receiver for forcing fluid into said valve operating means to open the inlet valve, whereby the pump can be operated at a moderate speed by the use of high pressure fluid. 90

2. In a fluid pressure pump, the combination with a closed receiver for the water to be pumped having an inlet for water, and an inlet for fluid under pressure for forcing the water out of the receiver, a valve for controlling the admission of the pressure fluid, hydraulic means for opening said valve, a cylinder for containing water, means for admitting high pressure fluid into said cylinder above the water, and means for conducting water from the cylinder into said valve opening means when the water in said cylinder is under pressure for operating said means slowly and opening the valve. 100

3. In a fluid pressure pump, the combination with a closed receiver for the water to be pumped having an inlet for admitting fluid under pressure on the surface of the water, a valve for controlling the admission of pressure fluid, a motor, a lever operated by the motor connecting with said valve for opening it, a chamber containing water, means for admitting high pressure fluid into said chamber above the water, and a pipe in said chamber for conducting water from the chamber into the motor when the water in said chamber is put under pressure for operating the lever. 110

4. In a fluid pressure pump, the combination with a closed receiver for the water to be pumped having an inlet for admitting fluid under pressure over the water in the receiver, a valve for controlling the admission of fluid through said inlet, a cylinder and piston having connections for opening 120

85

5 said valve, a pressure chamber for containing water, means for admitting high pressure fluid into the chamber over the water, means for conducting water from the chamber into the motor when the water in said chamber is under pressure to operate the motor, a valve for controlling the admission of pressure fluid into the chamber, a float in the receiver, and means connected with said

10 float for opening said valve when the float rises above a predetermined height.

5. In a fluid pressure pump, the combination with a closed receiver for the water to be pumped having an inlet for fluid under pressure for forcing the water out, a valve for controlling the inlet, a motor for opening said valve, means operated by fluid under pressure for forcing water into said motor to operate it, whereby the motor can be operated at a moderate speed with high pressure fluid, a valve for controlling the admission of pressure fluid into said water forcing means, a float in the receiver, and means connected with said float for opening said valve when the float rises above a predetermined height.

6. In a fluid pressure pump, the combination with a pressure admission valve and means for operating the valve, of a cylinder for containing water, means for admitting high pressure fluid into said cylinder above the water, and means for conducting water from the cylinder into said valve opening means when the water in said cylinder is under pressure for operating said means slowly and opening the valve, said pressure-admitting means comprising a valve, a yoke connected with the valve, a lost motion connection for reciprocating the yoke, a pivoted float, and a lever connected with the float for operating the yoke when the float rises or falls beyond a certain height.

7. In a fluid pressure pump, the combination with a pressure admission valve and means for operating the valve, of a cylinder for containing water, means for admitting high pressure fluid into said cylinder above the water, and means for conducting water from the cylinder into said valve opening means when the water in said cylinder is under pressure for operating said means slowly and opening the valve, said pressure-admitting means comprising a valve, a yoke connected with the valve, a pivoted float, a lever connected with the float for operating the yoke having two arms at an angle to each other arranged to swing with the float, a weighted lever having one arm extending between said two arms and arranged to be operated by them and having an arm extending into the yoke to constitute a lost motion means for operating it.

8. In a fluid pressure pump, the combination with a fixed air tight receiver having an outlet and inlet connection in the bottom

thereof, check valves therein for preventing water flowing in the wrong direction through them, a float in said receiver, a valve rod, a lost motion connection between the float and valve rod for operating the latter upon the raising of the float, means controlled by said valve rod for admitting fluid under pressure to said receiver and driving water out of it, and means constantly pressing the said valve rod to hold it in the position to which the float moves it.

9. In a device of the character described, the combination with a receiver, and means for introducing fluid into said receiver above the liquid therein under pressure, of means for controlling the admission of fluid under pressure comprising a hollow float in the receiver filled with air, having means for conducting fluid from the bottom of said float by gravity once during each cycle of operations.

10. A steam pressure pump comprising a stationary receiver having an outlet below the water thereof and an inlet for fluid under pressure, a valve for controlling said inlet, and means operated by the rise of the water level in said receiver, when it rises above a predetermined level, for positively opening said valve to admit fluid pressure above the water in the receiver, said receiver having a normally open inlet for water opening therein above the high water level to prevent agitation of the contents by the admission of water.

11. In a steam pressure pump, the combination of a stationary receiver having a water outlet, an inlet for fluid under pressure, a valve for controlling said inlet, a fluid motor comprising a piston, a pilot valve for controlling the admission of fluid pressure to said motor to move the piston, a float in the receiver, means operated by said float for opening said pilot valve when the float rises and admitting pressure to said motor, and means operated by the piston for positively opening the first named valve to admit fluid pressure above the water in the receiver.

12. In a fluid pressure pump, the combination with a stationary air tight receiver for water, a float therein, a piston, and a cylinder having an admission and exhaust port, of means connected with the piston for admitting fluid under pressure into said receiver and forcing the water out of it, a valve for controlling the admission of fluid through said port, means for yieldingly holding the pilot valve in extreme closed or open position, a movable rod adapted to move said pilot valve to open or closed position, and a lost motion connection with said float for operating said rod.

13. In a fluid pressure pump, the combination with a stationary receiver for water, a float therein, a piston, and a cylinder, of

means connected with the piston for admitting pressure fluid into said receiver and forcing the water out of it, means for conducting fluid into the cylinder behind the piston, a connection having an admission port for controlling the admission of fluid to said cylinder, a valve, means for yieldingly holding the pilot valve in position to close said port, a movable rod adapted to move said valve into position to admit pressure to the cylinder, and a connection with said float for operating said rod, said float consisting of a hollow body, said float having means carried thereby for conducting liquid out of the float by gravity when the float rises.

14. In a fluid pressure pump, the combination with a stationary air tight receiver for water, a float therein, a pressure admitting valve, a piston and a cylinder, said cylinder having an admission port for conducting fluid into the cylinder behind the piston, of a pilot valve, means for yieldingly holding the pilot valve in either closed or open position, a rod adapted to move said pilot valve, a connection with said float for operating said rod, a weight supported by said piston and movable therewith, and a lever for operating the first named valve having means for normally holding the valve closed, said lever being in position to be operated by said weight when it rises, to open the first named valve.

15. In a fluid pressure pump, the combination with a receiver for water, a float therein, an admission valve, a piston, and a cylinder, said cylinder having an admission port for conducting fluid into the cylinder behind the piston, of a pilot valve, means for holding the pilot valve in position to cut off pressure from said port, a rod adapted to move said pilot valve into position to admit pressure to the cylinder, a connection with said float for operating said rod, and a lever for operating said admission valve having means for normally holding the valve closed, said lever being in position to be operated by said piston, when it rises, to open the valve.

16. In a fluid pressure pump, the combination with a stationary air tight receiver for water, a float therein, a piston and a cylinder having an admission port, an exhaust port, said cylinder having an end seat for the piston, and packing on the end of the piston to make the piston water tight when the pump is discharging, of means connected with the piston for admitting fluid under pressure into said receiver above the water, a pilot valve, means for moving said pilot valve out of its normal position to admit pressure to the cylinder, and a connection with said float for operating said means.

17. A steam pressure pump comprising a stationary receiver having an outlet below

the water level thereof and an inlet for fluid under pressure, a valve for controlling said inlet, means for positively opening said valve to admit fluid pressure above the water in the receiver, said means comprising a lever having a weight for normally holding the lever down, a motor for operating the lever, a lever in the receiver, a float thereon, a counterweight on the lever to be operated by the float, and a valve for controlling said motor arranged to be operated by the last named lever.

18. A steam pressure pump comprising a stationary receiver having an outlet below the water level thereof and an inlet for fluid under pressure, a valve for controlling said inlet, means for positively opening said valve to admit fluid pressure and force water from the receiver, said means comprising a lever having a weight for normally holding the lever down, and means for raising said lever and its weight, a lever pivoted in said receiver and having a float at one end and a counter-weight at the other, a valve operating lever operated by said float lever, and a valve for admitting pressure to the weight raising means controlled by the last named lever.

19. A pressure pump comprising a stationary receiver having an inlet for fluid under pressure, a baffle plate under, but spaced from, said inlet to prevent agitation of the surface of the water in the receiver and prevent water hammer, a valve for controlling said inlet, a lever pivoted in said receiver and having a float at one end and a counterweight at the other, a valve operating lever operatively connected with said lever, and a valve for admitting pressure to the valve controlled by the last named lever.

20. A steam pressure pump comprising a stationary receiver having an outlet below the water level thereof and an inlet for steam, a valve for controlling said inlet, means, operated by the rise of the water level in said receiver, for positively opening said valve to admit steam pressure and force water from the receiver, said means comprising a lever for operating said valve having a weight for normally holding the lever down and the valve closed, a motor having means for raising said lever and its weight, a valve for controlling the admission of water having a spray nozzle connected with it and located in the receiver to introduce a spray and condense the steam in the receiver, said weighted lever having connections for operating the last named valve, and means connected with said motor for holding the lever in position to open one valve and close the other.

21. A steam pressure pump comprising a stationary receiver having an outlet below the water level thereof and an inlet for fluid under pressure, a valve for controlling said

inlet, means for positively opening said valve to admit fluid pressure and force water from the receiver, said means comprising a lever having a weight for normally holding the lever down, means for raising said lever and its weight and opening said valve comprising a motor connected with the lever, a spray water admitting valve for the receiver, and means connecting the lever and water valve to hold the latter closed when the steam valve is open.

22. In a fluid pressure pump, the combination with a stationary closed receiver, of valve controlled means for admitting fluid under pressure to said receiver, valve controlled means for relieving the receiver of fluid pressure, a float in the receiver, a fluid operated motor having connections for controlling both valves comprising a movable member arranged to hold the first named valve controlled means open and to allow it to close when the piston rises, and to first positively open the second valve controlled means, and means controlled by the float for operating the motor.

23. A steam pressure pump comprising a stationary receiver having an outlet below the water level thereof and an inlet for fluid under pressure; a valve for controlling said inlet, means operated by the rise of the water level in said receiver for positively opening said valve to admit fluid pressure and force water from the receiver, said means comprising a lever for operating said valve having a weight for normally holding the lever down and the valve closed, and means for raising said lever and its weight.

24. In a fluid pressure pump, the combination with a stationary closed receiver, of means for admitting water to said receiver, a relief valve, valve controlled means for admitting fluid under pressure to said receiver for forcing the water out, a float in the receiver, and a fluid operated motor controlled by said float having connections for controlling both valves to close the relief valve before the fluid pressure valve is opened.

25. A fluid pressure pump, comprising a

closed receiver for the water to be pumped 50 having an inlet for fluid under pressure for forcing the water out, a valve for controlling the inlet, a motor for opening said valve, means operated by fluid under pressure for forcing water into said motor to 55 operate it, whereby the motor can be operated at a moderate speed with high pressure fluid, and means for controlling the admission of pressure fluid into said water forcing means.

26. A piston pressure device for operating a piston in a cylinder comprising a water chamber, means for conducting a fluid under pressure into the top of said chamber to exert pressure on the water therein, and a 65 tube connected with the chamber below the water level thereof connected to the cylinder for conducting water into the cylinder back of its piston.

27. A fluid pressure pump, comprising a 70 closed receiver for the water and means for controlling the admission of fluid pressure into the receiver to force the water out, said controlling means comprising a hollow cast aluminum float in the receiver, a tubular arm pivoted in the receiver to the end of which the float is connected and with the interior of which it communicates, said arm being arranged tangent to or in line with the bottom of said float, whereby when the float 75 is elevated the water will drain by gravity from the float, and means for discharging water from the interior of said arm outside the receiver.

28. A fluid pressure pump, comprising a 80 closed receiver and means for controlling the admission of fluid pressure into the receiver to force the water out, comprising a hollow float in the receiver, a tubular arm pivoted in the receiver to the end of which 85 the float is connected and with the interior of which it communicates, said arm being arranged in line with the bottom of said float, and means for discharging water from the interior of said arm outside the receiver. 90

In testimony whereof I have hereunto affixed my signature.

NELSON B. JOHNSON.
